A. H. STEBBINS

CONCENTRATOR BECK

Filed Jan. 19, 1926

UNITED STATES PATENT OFFICE.

ALBERT H. STEBBINS, OF LOS ANGELES, CALIFORNIA.

CONCENTRATOR DECK.

Application filed January 19, 1926. Serial No. 82,183.

This invention relates to concentrator decks having riffles extending over the deck surface, and more particularly to the construction and arrangement of the riffles.

5 The decks of table concentrators are commonly provided with a laterally inclined deck surface over which a number of riffles extend, and these riffles are arranged so that the lighter materials will flow laterally over the riffles toward the lower side of the deck surface, while the concentrates are directed more or less lengthwise of the deck toward a concentrate wall. In many cases the riffles are inclined to the length of the deck so 10 that they will direct the concentrate toward the upper side of the inclined deck surface.

It sometimes happens that the coarse materials tend to clog between the riffles instead of flowing lengthwise therebetween, 20 and the very fine materials may tend to pack between the riffles, which is objectionable. The tendency of the materials to clog or pack between the riffles may be prevented by increasing the distance between the riffles, 25 but this reduces the number of riffles acting to separate the materials, and is open to the further objection that if the lateral inclination of the deck surface is quite steep the bank of materials resting against one riffle 30 may not extend entirely across the wide space between a pair of riffles, whereupon some of the air apertures in the deck surfaces will not be covered by the materials being treated.

35 Having in mind the foregoing, the present invention relates to the construction and arrangement of the riffles whereby they may be spaced sufficiently far apart to prevent the materials from clogging or packing therebetween, while at the same time danger of the materials shifting laterally sufficiently to uncover some of the air apertures in the deck surface is avoided.

An important feature of the present invention therefore resides in a deck surface 40 having a series of riffles that are spaced a substantial distance apart and having one or more low riffles disposed between the widely spaced higher riffles.

50 It is found that the tendency of the materials to pack or clog between riffles that are close together decreases as the finer dust-like materials are removed; that is, the tendency of the materials to pack or clog between the riffles, decreases as the materials approach the concentrate wall or discharge

end of the deck. It therefore follows that when a combination of high and low riffles is employed, in accordance with the present invention, the height of the low riffles may 60 be increased near the concentrate wall without appreciably increasing the tendency of the materials to pack or clog, and this is desirable as it increases the separating action of the riffles upon the materials that pile up 65 against the concentrate wall.

The various features of the invention and novel combination of parts will be best understood from the following description when read in connection with the accompanying drawing, wherein:—

Fig. 1 is a perspective view of a concentrate deck provided with riffles constructed in accordance with the present invention.

Fig. 2 is an enlarged sectional perspective view taken on the line 2—2 of Fig. 1; and

Fig. 3 is a sectional view taken thru a portion of the deck parallel to the riffles.

The concentrator deck shown may for the 80 most part have any usual or preferred construction, and may comprise a closed casing or receptacle 10 adapted to receive the air which is forced upwardly thru apertures in the deck surface 11. Air under 85 pressure may be supplied to the chamber below the deck surface by a pipe 12 connected by the flexible connection 13 to the hood 14 at one end of the casing 10.

The deck may have the usual concentrate 90 wall 15 provided with the buffer blocks 16 against which the materials are directed by the riffles to be described. The deck surface 11 is usually supported at a transverse inclination as shown, so that the lighter materials will flow laterally over the riffles toward the lower side of the deck, and the deck surface shown has the air apertures 17 for directing currents of air upwardly thru the materials being treated.

The deck so far described forms no essential part of the present invention and may have the usual or any preferred construction. As above indicated the present invention relates more particularly to the 105 construction and arrangement of the riffles now to be described.

In accordance with the present invention the higher riffles 18 are positioned a substantial distance apart, as shown in the 110 drawings, and between the pairs of high riffles 18 are provided one or more low riffles

19. In the embodiment of the invention illustrated two low riffles 19 are provided between each pair of high riffles 18, but the number of low riffles may be increased or 5 decreased as found desirable. The low riffles 19 do not rise from the deck surface a sufficient distance to permit the materials to clog or pack therebetween, and the distance between the high riffles 18 is sufficiently 10 great to prevent clogging or packing between them.

The low riffles, as will be apparent from Fig. 2, serve to form one or more blanks 20 of the materials between a pair of high riffles 18 to thereby prevent the apertures in the deck surface from being entirely uncovered by the failure of a single bank of materials to extend entirely across the space between two high riffles. The low riffles help also to promote 15 separation of the materials.

It is often desirable that as many high riffles be provided to terminate adjacent the concentrate wall as other conditions may warrant, and to this end the height of the 20 low riffles 19 may be increased adjacent the concentrate wall as indicated by 21. This may be done without appreciably increasing the tendency of the materials to pack or clog 25 between the riffles, because most of the light fine materials which are likely to retard the flow of the materials between the riffles have 30 been removed before the concentrates approach the concentrate wall.

In some cases it may be unnecessary to 35 extend the low riffles all the way back to the wall 22 at the material receiving end of the deck because the layer of materials upon this portion of the deck surface may be sufficiently thick to prevent the apertures from 40 becoming uncovered. Some of the low riffles are therefore shown as terminating short of this wall as indicated by 23. The materials are fed to the deck by the hopper 24.

From the foregoing it will be seen that a 45 distinct advantage in the operation of a con-

centrator deck is secured by providing the deck with high and low riffles in accordance with the present invention.

What is claimed is:—

1. A deck for a concentrate table, comprising in combination, a deck surface that is supported at a transverse inclination, high riffles extending diagonally over the deck surface and spaced a substantial distance apart to prevent the materials from clogging 55 between them, and low riffles disposed between the high riffles and having less length than the high riffles so that they do not extend over that portion of the deck surface lying near the feed hopper. 60

2. A deck for a concentrator table comprising in combination, a deck surface that is supported at a transverse inclination, high riffles extending diagonally over the deck surface and spaced a substantial distance 65 apart to prevent the materials from clogging between them, and two low riffles disposed between a pair of high riffles and having less length than the high riffles so that they do not extend over that portion of the deck 70 surface lying near the feed hopper.

3. A deck for a concentrator table, comprising in combination, a deck surface that is supported at a transverse inclination, high riffles extending diagonally over the deck surface and spaced a substantial distance 75 apart to prevent the materials from clogging between them, low riffles disposed between the high riffles and each having its height gradually increased near the concentrate 80 wall to promote piling up of the concentrates against said wall, and the low riffles having less length than the high riffles so that they do not extend over that portion of the deck surface lying near the material receiving end of the deck. 85

In testimony whereof, I have signed my name to this specification.

ALBERT H. STEBBINS.
